DISPLAY HOLDER STRUCTURE

Hardie W. Brown, Dallas, Tex.

Application May 15, 1940, Serial No. 335,413

3 Claims. (Cl. 40—125)

This invention relates to a holder structure designed primarily for displaying the identification number of a residence, but it is to be understood that a holder structure, in accordance with this invention is for employment in any connection for which it may be found applicable.

The invention aims to provide, in a manner as hereinafter set forth, a holder structure for the purpose set forth, including a standard or supporting element having means for anchoring it in the ground in front of a residence and means for displaying on opposite sides of the standard the identification number of the residence to enable pedestrians walking in opposite directions or occupants of vehicles travelling in opposite directions to conveniently read such number.

The invention further aims to provide, in a manner as hereinafter set forth, a holder structure for the identification number of a residence to enable a person to readily locate a residence being sought.

The invention further aims to provide, in a manner as hereinafter set forth, a holder structure for the purpose referred to including light reflecting means for directing attention thereto when one is endeavoring to locate the identification number of a residence.

The invention further aims to provide, in a manner as hereinafter set forth, a holder structure for the purpose referred to which is simple in its construction and arrangement, strong, durable, compact, thoroughly efficient in its use, readily assembled, expeditiously installed in house number identifying positions, attractive, distinctive, pleasing in appearance, and inexpensive to manufacture.

Embodying the aims aforesaid and others which may hereinafter appear, the invention consists of the novel construction, combination and arrangement of parts as will be more specifically referred to and illustrated in the accompanying drawing, wherein are shown embodiments of the invention, but it is to be understood that changes, variations and modifications may be resorted to which fall within the scope of the invention as claimed.

A holder structure for the purpose set forth and in accordance with this invention will include as an element thereof a comparatively thin flat support for disposing vertically, and preferably for anchoring in the lawn in front of a residence, or it may be secured vertically to a bracket or other anchor, the support having both of its sides

provided with the simulation of an object, such, by way of example, as a bird or animal. Two forms of the invention are shown and described, and by way of example the simulation employed in one of the forms is an owl and in the other form a dog or puppy. It is to be understood that any desirable simulation may be employed other than referred to in connection with a holder structure, in accordance with this invention for the purpose of making such structure attractive, distinctive and pleasing in appearance.

In the drawing:

Figure 1 is an elevation looking towards one side of a holder structure in accordance with this invention.

Figure 2 is a section on line 2—2 Figure 1.

Figure 3 is a section on line 3—3 Figure 1, and

Figure 4 is an elevation looking towards one side of a modified form of holder structure in accordance with this invention.

With reference to Figures 1 to 3, the holder structure, generally indicated at 5, includes a standard or supporting element 6 having an upper section 7 and a lower section 8. The section 7 includes an upper end portion 9, an intermediate portion 10 and a lower end portion 11. The upper end portion 9 is made attractive and distinctive and for such purpose it is so formed to simulate the ovoidal-shaped body 12 and the round head 13 of an owl on both sides thereof.

The eye simulations of each owl simulation are in the form of a pair of spaced colored disc-like reflectors 14, 15, which are secured by suitable cementitious material to head 13. A pair of reflectors are arranged on each side of said head.

The intermediate portion 10 of the section 7 is of rectangular contour and is extended laterally in opposite directions, as at 16, 17, with respect to the body simulation 12. The lower end of portion 9 merges into the top edge of portion 10 centrally of the latter, as at 18.

The lower end portion 11 of section 7 is of less width and length with respect to portion 9, is of tapered contour and merges at its top into the lower edge of portion 10 centrally of the latter, as at 19.

The section 7 preferably will be formed from a single length of sheet metal of the desired thickness and length. It is to be understood that section 7 may be formed from any other suitable material.

The section 8 constitutes an anchoring means for element 6 and it is formed of a round bar 20, of the desired length having one side of its upper terminal portion 21 rabbeted, as at 22. The said upper terminal portion 21 is flattened to 23

provide it being of greater width than the remaining part of bar 20, and it is arranged against the lower part of the outer fact of the lower end portion 11 of the section 7. The terminal portion 21 is anchored to the outer face of portion 11 and centrally of the latter by the holdfast means 23. The bottom edge of the portion 11 of section 7 is disposed in proximity to the ledge or shoulder 24 formed by the rabbet 22. The section 8 aligns with the lengthwise median of section 7.

The holder structure 5 includes two pair of oppositely disposed spaced parallel display retainers. The retainers of one pair are indicated 15 at 25, 26 and those of the other pair at 27, 28. Each retainer is in the form of a channel-shaped strip. The retainers 25, 27 open downwardly. The retainers 26, 28 open upwardly. Each retainer is open at each end and is of less length 20 than the length of the rectangular portion 10 of the section 7. The retainers 25, 26 are positioned against one side of portion 10 in superposed spaced parallel relation and are equally spaced from the ends of portion 10. The retainers 27, 25 28 are positioned against the other side of portion 10 in superposed spaced parallel relation and are equally spaced from the ends of portion 10. The retainers are spaced equidistant from 30 the top and bottom edges of the said portion 10 of section 7.

The retainers are detachably secured to both sides of the said portion 10 and maintained in the position aforesaid by a set of spaced holdfast devices 29, four in number and each being 35 common to a pair of retainers. The holdfast devices 29 also constitute removable abutment means for releasably maintaining or confining the display to be referred to in the retainers. Each holdfast device 29 is in the form of a headed 40 bolt 30 and a nut 31. The bolts are passed through the retainers in proximity to the ends of the latter and through spaced parts of the portion 10 of section 7. The heads of the bolts abut one pair of retainers and the nuts bind 45 against the other pair of retainers. The bolts extend across the channels formed by the retainers inwardly of the open outer ends of the channels.

The display referred to will be the identification 50 number of a dwelling or a place of business and will be formed of a set of panels of equal dimensions arranged in sidewise abutting relation. The panels will be provided with digits which when combined will set forth such identification number as indicated at 32. By way of example, the 55 number of panels of the set are shown as four. Each panel is indicated at 33 and its digit at 34. If it does not require four digits to provide the number 32, say but three or two then blank panels 60 are employed to aggregate four. It is to be understood that certain of the panels may be provided with "oughts" and that the number of the panels may be greater than four, if so the length of the retainers will be increased accordingly. A set of panels is slidably mounted in the 65 retainers 25, 26 and a set of panels is slidably mounted in the retainers 27, 28. The mounting of the panels relative to the retainers is had when the holdfast devices 29 have been removed. After 70 the panels have been positioned in the retainers, one pair of retainers with a set of panels therein is positioned against one side of the portion 10 of section 7, and the bolts of the holdfast devices are extended through the said pair of retainers and 75 said portion 10, and when the bolts are so posi-

tioned they will extend beyond the other side of portion 10. The other pair of retainers, with the other set of panels therein are mounted on the extended portions of the bolts, and the nuts 31 are then screwed home whereby the said pairs of retainers with panels therein will be removably secured to opposite sides of the portion 10. When the holdfast devices 29 are in position securing the pairs of retainers and sets of panels to the section 7 of element 6, the bolts 30 act to releasably maintain or confine the panels in the retainers. The form of the latter provides for the inter-changing of the panels when desired.

The modified form of the holder structure shown by Figure 4 is designated at 35 and it includes a standard or supporting element 36 so formed as to have both of its sides simulate the appearance of a dog or puppy. The element 36 includes a pair of spaced aligned anchors 37, 38 therefor in the form of depending rods of the 20 desired length. The structure 35 includes two pairs of retainers; one for correlation with one side and the other for correlation with the other side of element 36. Each pair of retainers is to display a set of panels. The pairs of retainers 25 are of the same form and arrangement as the retainers of the holder structure 5. But one pair of retainers is illustrated with respect to element 36 and such pair is indicated at 39, and but one set of panels are illustrated with respect to structure 35 and it is designated 40. The eye simulations of each of the dog or puppy simulations are in the form of a pair of spaced colored reflectors 41 arranged and mounted in the same manner as the reflectors 14, 15. Preferably the reflectors 35 of each form will be red.

The term object employed in the claims is to be considered as generic to the simulation of a bird, an animal, the human face, a man or a child.

Instead of having the numbers in the panels, it is obvious, of course, that letters can be employed so that if desired the display can be used for such purposes as "Rooms," "For Sale," etc. It will be noted from the description herein that this device 45 lends itself most particularly to low cost manufacturing and is extremely durable. With ordinary care this device will last indefinitely.

What I claim is:

1. In a holder structure for the purpose set 50 forth, an upstanding supporting element having its lower portion consisting of an anchoring means therefor, a pair of spaced parallel oppositely disposed channel-shaped one piece retainers arranged transversely of each side of said element 55 and adapted to hold a display, said retainers being open at each end and formed with a pair of aligned transverse openings adjacent each end, said pairs of retainers being arranged against said element intermediate its ends, and a set of 60 removable holdfast devices common to said pairs of retainers and correlating with said openings for detachably securing said retainers to said element, said devices constituting abutments for removably confining the displays in the pairs of 65 retainers.

2. In a display holder structure, an upstanding supporting element including an upper portion, a lower portion and an intermediate portion, said upper portion being so formed to direct attention 70 thereto at each side thereof, said intermediate portion being of rectangular contour and extending laterally in opposite directions with respect to the said other portions, means secured to said lower portion and depending from the latter for 75

anchoring said element, a pair of spaced parallel oppositely disposed channel-shaped one piece retainers arranged horizontally of each side of said intermediate portion and adapted to hold a display, said retainers being open at each end and formed with a pair of aligned transverse openings adjacent each end, and a set of removable holdfast devices common to said pairs of retainers and correlating with said openings for detachably securing said retainers to said intermediate portion, said devices constituting abutments for removably confining the displays in the pairs of retainers. 5

10

3. In a display holder structure, an upstanding supporting element including an upper portion, a lower portion and an intermediate portion, said upper portion being so formed to direct attention thereto at each side thereof, said intermediate portion being of rectangular contour and extending laterally in opposite directions with re-

15

20

spect to the said other portions, means secured to said lower portion and depending from the latter for anchoring said element, a pair of spaced parallel oppositely disposed channel-shaped one piece retainers arranged horizontally of each side of said intermediate portion and adapted to hold a display, said retainers being open at each end and formed with a pair of aligned transverse openings adjacent each end, and a set of removable holdfast devices common to said pairs of retainers 10 and correlating with said openings for detachably securing said retainers to said intermediate portion, said devices constituting abutments for removably confining the displays in the pairs of retainers, said upper portion being of greater length 15 than the intermediate and lower portions, said lower portion being disposed centrally with respect to the intermediate portion and tapered. 5
